UNITED STATES PATENT OFFICE.

JOHN JAMES CONNOLLEY, OF POQUONOCK, CONNECTICUT.

MIXING APPARATUS.

1,204,846.

Specification of Letters Patent.

Patented Nov. 14, 1916.

Application filed July 15, 1916. Serial No. 109,557.

To all whom it may concern:

Be it known that I, JOHN J. CONNOLLEY, a citizen of the United States, residing at Poquonock, in the county of Hartford and 5 State of Connecticut, have invented certain new and useful Improvements in Mixing Apparatus, of which the following is a specification, reference being had to the accompanying drawings.

10 This invention relates to certain improvements in mixing apparatus and has relation more particularly to a device of this general character especially designed and adapted for use in connection with the textile industry; and it is an object of the invention to provide a device of this general character having novel and improved means whereby differing stocks such as cotton and wool may be thoroughly and effectively commingled. 15 It is also an object of the invention to provide a novel and improved device of this general character which serves to thoroughly comminute the stock and whereby the same after being mixed is discharged 20 in substantially an automatic manner.

Furthermore it is an object of the invention to provide a device of this general character having novel and improved means whereby the stock after it has been mixed 25 and substantially at the time it is discharged has applied thereto an oil solution for a purpose which is well known in the trade.

The invention consists in the details of 30 construction and in the combination and arrangement of the several parts of my improved mixing apparatus whereby certain important advantages are attained and the device is rendered simpler, less expensive 35 and otherwise more convenient and advantageous for use, all as will be hereinafter more fully set forth.

The novel features of the invention will 40 hereinafter be definitely claimed.

45 In order that my invention may be the better understood, I will now proceed to describe the same with reference to the accompanying drawings, wherein—

Figure 1 is a view in side elevation illustrating a mixing apparatus constructed in accordance with an embodiment of my invention; Fig. 2 is a vertical longitudinal sectional view taken through the device as herein embodied; Fig. 3 is a sectional view 55 taken substantially on the line 3—3 of Fig.

1; Fig. 4 is a sectional view taken substantially on the line 4—4 of Fig. 1; and Fig. 5 is a detail elevational view of one of the pins herein employed.

As disclosed in the accompanying drawings, 60 1 denotes an elongated container of predetermined dimensions and having its upper face open and divided at substantially its vertical center into the compartments A and B through the medium of the bars 2 arranged in parallelism and disposed longitudinally of the container 1, each of said bars 2 being preferably substantially diamond-shape in cross section. The bottom 3 of the container 1 is perforated so 65 that the same will serve as a screening element for the discharge of dust or dirt which may be separated from the stock during the operation of the device. For this reason the container 1 is maintained, through the 70 medium of the supports 4, in predetermined spaced relation relative to the supporting surface for the device.

Positioned within the upper compartment 75 A and disposed transversely of the container 1 are the cylinders 5 having radiating therefrom the pins 6 which serve to engage the stock as deposited within the container through its open top and effectively tear the stock and as the stock is 80 comminuted it drops between the bars 2 into the lower compartment B, whereby the stock is further commingled through the medium of the transversely disposed cylinders 7. The cylinders 7 also have radiating 85 therefrom the pins 8. It is to be noted that the pins 6 extend downwardly through the spaces between the bars 2 so as to effectively act upon the stock within the upper compartment A in order to further facilitate 90 the comminution thereof.

The cylinders 5 and 7 are provided with shafts 9 extending beyond a side of the container 1 whereby the same may be operatively connected preferably through the 100 belts 10 so that said cylinders will rotate in unison and preferably from a common source of power as indicated at 11. It is also preferred that the location of the cylinders 7 within the lower compartment B be 105 in such a direction as to force the stock toward the discharge end of said compartment and which is in communication with the chamber 12 provided with the discharge chute 14. Rotatably mounted within the 110

chamber 12 is the throwing cylinder 15 provided with the radiating teeth 16 and which is caused to rotate in such a direction as to throw the stock as delivered within the 5 chamber 12 out upon the chute 14 so that said stock may be suitably discharged.

As herein disclosed, the throwing cylinder 15 is provided with a shaft 17 operatively connected preferably through the medium 10 of the belt 18 with a suitable source of power.

Disposed transversely of the chamber 12 and at a point above the throwing cylinder 15 is a spraying or sprinkling pipe 19 in 15 communication with a suitable source of supply, as indicated at 20. By this means it will be perceived that the oil solution generally employed in the mixing of wool or cotton may be conveniently and effectively applied to the stock after the same 20 has been delivered within the chamber 12 and before the same is discharged therefrom.

While the pins 6 and 8 may be of various 25 designs I prefer to employ the arrangement disclosed in the accompanying drawings wherein each of said pins is provided with an inner threaded portion 21 whereby the same may be detachably engaged with its 30 coacting cylinder and wherein the extended portion thereof is blade-like and terminating in a point so that an effective action may be had upon the stock.

From the foregoing description, it is 35 thought to be obvious that a mixing apparatus constructed in accordance with my invention is of an extremely simple and comparatively inexpensive nature and is particularly well adapted for use by reason of 40 the convenience and facility with which it may be assembled, and it will also be obvious that my invention is susceptible of some change and modification without material departure from the principles and spirit 45 thereof and for this reason I do not wish to be understood as limiting myself to the precise arrangement and formation of the several parts herein shown in carrying out my invention in practice, except as herein- 50 after claimed.

I claim:

1. A device of the character described comprising a container, having its top face open, substantially horizontally disposed 55 bars dividing said container into vertically related compartments, cylinders rotatably mounted within each of said compartments and provided with tearing means, and means for rotating the cylinders.

60 2. A device of the character described comprising a container, having its top face open, substantially horizontally disposed bars dividing said container into vertically 65 related compartments, cylinders rotatably mounted within each of said compartments,

and means for rotating the cylinders, each of said cylinders being provided with teeth extending therefrom.

3. A device of the character described comprising a container, having its top face 70 open, substantially horizontally disposed bars dividing said container into vertically related compartments, cylinders rotatably mounted within each of said compartments, and means for rotating the cylinders, each of said cylinders being provided with teeth extending therefrom, the teeth of the upper cylinders passing between the bars and into the lower compartment.

4. A device of the character described 80 comprising a container, having its top face open, substantially horizontally disposed bars dividing said container into vertically related compartments, cylinders rotatably mounted within each of said compartments 85 and provided with tearing means, and means for rotating the cylinders, the bottom of the container being perforate to afford a screening element.

5. A device of the character described 90 comprising a container having its top face open, substantially horizontally disposed bars dividing said container into vertically related compartments, cylinders rotatably mounted within each of said compartments 95 and provided with tearing means, means for rotating the cylinders, a chamber in communication with the lower compartment at the discharge end thereof, and a throwing member mounted within the chamber.

6. A device of the character described comprising a container having its top face open, substantially horizontally disposed bars dividing said container into vertically related compartments, cylinders rotatably 105 mounted within each of said compartments, means for rotating the cylinders, a chamber in communication with the lower compartment at the discharge end thereof, and a throwing member mounted within the chamber, said throwing member including 110 a cylinder provided with outwardly disposed teeth.

7. A device of the character described comprising a container having its top face 115 open, substantially horizontally disposed bars dividing said container into vertically related compartments, cylinders rotatably mounted within each of said compartments 120 and provided with tearing means, means for rotating the cylinders, a chamber in communication with the lower compartment at the discharge end thereof, a throwing member mounted within the chamber, and a 125 sprinkling member within the chamber in communication with a suitable source of supply and positioned above the throwing member.

8. A device of the character described comprising a container having its top face 130

open, substantially horizontally disposed bars dividing said container into vertically related compartments, cylinders rotatably mounted within each of said compartments and provided with tearing means, means for rotating the cylinders, a chamber in communication with the lower compartment at the discharge end thereof, a throwing member mounted within the chamber, and means for rotating the cylinders with the cylinders in the lower compartment traveling in a direction to force the material deposited therein toward the discharge end thereof.

9. A mixer of the character described including a container having its top open, bars disposed longitudinally of the container and dividing the same into vertically related compartments, a tearing member arranged within the upper compartment, the lower compartment being provided with a discharge, and means for forcing the material delivered within the lower compartment through the discharge thereof.

10. A mixer of the character described including a container having its top open, bars disposed longitudinally of the container and dividing the same into vertically related compartments, a tearing member arranged within the upper compartment, the lower compartment being provided with a discharge, and means for forcing the material delivered within the lower compartment through the discharge thereof.

lower compartment being provided with a discharge, means for forcing the material delivered within the lower compartment through the discharge thereof, a chamber in communication with the lower compartment of the discharge thereof, and a throwing member mounted within the chamber.

11. A mixer of the character described including a container having its top open, bars disposed longitudinally of the container and dividing the same into vertically related compartments, a tearing member arranged within the upper compartment, the lower compartment being provided with a discharge, means for forcing the material delivered within the lower compartment through the discharge thereof, a chamber in communication with the lower compartment of the discharge thereof, and a throwing member mounted within the chamber, and a sprinkling member within the chamber in communication with a suitable source of supply.

In testimony whereof I hereunto affix my signature in the presence of two witnesses.

JOHN JAMES CONNOLLEY.
